UNITED STATES PATENT OFFICE.

HENRY NORDMANN, OF BROOKLYN, NEW YORK.

DESIGN FOR CARPET.

SPECIFICATION forming part of Design No. 11,832, dated June 29, 1880.

Application filed February 12, 1880. Term of patent 3½ years.

To all whom it may concern:

Be it known that I, HENRY NORDMANN, of the city of Brooklyn, State of New York, have invented a new and original Design for Carpet, of which the following is a specification.

This invention relates to a new and original design for carpets, oil-cloths, and similar fabrics.

It consists in the novel grouping and configuration of figures, hereinafter more fully described and claimed.

The accompanying photograph illustrates a face view of a carpet having my new design.

The principal figure of the design is a central group, A, composed of flowers and spreading leaves. Around the central figure, A, are arranged an oval figure, B, with a scalloped border partly embracing said figure B; a diagonally-placed rectangular figure, C, with an ornamented border, a, along two sides thereof; a partially-rectangular figure, D, with an ornamented border, b, overlapping diamond figures E F G; a field, H, with leaves, flowers, and branches interspersed upon it; a figure, I, composed of angularly-bent stripes d d'; a polygonal figure, K, with a fretted border, d', and branches and circular figures e in its field, and a step-shaped rectangular figure, L, with tessellated ground-work and a spray of flowers and leaves superimposed on its ground. Above the figure L is an ornamented border, M. N is a diagonally-placed rectangular figure, abutting against the figure K, and O is a field containing a square, f, and rosettes, which ornament its surface. This field O is formed between the figures I, K, L, D, C, B, and N.

I claim—

1. The design for a carpet, consisting of the central group, A, substantially as shown.
2. The design for a carpet, consisting of the central group, A, and figure B, substantially as shown.
3. The design for a carpet, consisting of the group A and figure C, substantially as shown.
4. The design for a carpet, consisting of the group A and figures B C, substantially as shown.

5. The design for a carpet, consisting of the group A and figure D, substantially as shown.

6. The design for a carpet, consisting of the group A and figures B C D, substantially as shown.

7. The design for a carpet, consisting of the group A and figures E F G, substantially as shown.

8. The design for a carpet, consisting of the group A and figures B C D E F G, substantially as shown.

9. The design for a carpet, consisting of the group A and field H, ornamented substantially as shown.

10. The design for a carpet, consisting of the group A, figures E F G, and field H, ornamented substantially as shown.

11. The design for a carpet, consisting of the group A and figures C, O, and I, ornamented substantially as shown.

12. The design for a carpet, consisting of the group A and figures B C D E F G, field H, and figure I, ornamented substantially as shown.

13. The design for a carpet, consisting of the group A and figures E F G I and field H, ornamented substantially as shown.

14. The design for a carpet, consisting of the group A and figures B, O, and K, ornamented substantially as shown.

15. The design for a carpet, consisting of the group A, figures B C D E F G, field H, and figures I K, ornamented substantially as shown.

16. The design for a carpet, consisting of the group A and figures D and L, substantially as shown.

17. The design for a carpet, consisting of the group A and figures B C D E F G, field H, and figures I K L, ornamented substantially as shown.

18. The design for a carpet, consisting of the figure K and the border d', substantially as shown.

19. The design for a carpet, consisting of the figures K and N, substantially as shown.

20. The design for a carpet, consisting of the figures I, K, L, and N, substantially as shown.

21. The design for a carpet, consisting of the field O, with rosettes, and figure f, ornamenting its ground, substantially as shown. 22. The design for a carpet, consisting of the border M, substantially as shown. 23. The design for a carpet, consisting of the border M and figure L, substantially as shown. 24. The design for a carpet, consisting of the field O and figures B C I K N, ornamented substantially as shown.	25. The design for a carpet, consisting of the figures D E F G, substantially as shown. 26. The design for a carpet, consisting of the figures A, B, C, D, E, F, G, H, I, K, L, M, N, and O, ornamented substantially as shown.

HENRY NORDMANN.
